(57) **CLAIM**

The ornamental design for a rooftop tent for motor vehicle as shown and described.

DESCRIPTION

FIG. 1 is a perspective view of a rooftop tent for motor vehicle showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken line showing of the rooftop tent for motor vehicle is for the purpose of illustrating unclaimed portions of the rooftop tent for motor vehicle and forms no part of the claimed design.

1 Claim, 3 Drawing Sheets
